UNITED STATES PATENT OFFICE.

WALTER W. LOFLIN, OF NORFOLK, VIRGINIA.

VEST-WATCH-CHAIN HOLDER.

Application filed March 24, 1922. Serial No. 546,421.

To all whom it may concern:

Be it known that I, WALTER W. LOFLIN, a citizen of the United States, residing at Norfolk, in the county of Norfolk and State 5 of Virginia, have invented certain new and useful Improvements in a Vest-Watch-Chain Holder, of which the following is a specification.

This invention relates to a chain holding 10 device and more particularly to a novel and improved watch chain suspension button particularly applicable for attachment on a vest whereby the chain may be conveniently supported when extended across the 15 vest from one pocket to another.

One of the objects of the invention is the provision of a watch chain support in the nature of a button which will obviate the necessity of passing the chain through one 20 of the button holes of the vest when the said chain is extended across the vest and also permits of the attachment of one end of the chain thereto.

Another and a very important object of 25 the invention is the provision of a watch chain supporting device wherein the chain ring is disposed at right angles to the fastening means whereby the said device is attached to the material of the garment including provision whereby an insignia or 30 monogram may be placed on the face of the support.

With these and other objects in view, the invention consists in the construction 35 and novel combination of parts hereinafter fully described, illustrated in the accompanying drawings and pointed out in the subject matter being claimed, it being understood that various changes in the form, 40 proportion, size and minor details of construction, within the scope of the claim may be resorted to without departing from the spirit or sacrificing any of the advantages of the invention.

5. In the drawings, Figure 1 is a front view of the supporting device.

Figure 2 is a longitudinal sectional view of the same.

Figure 3 is a rear view.

50 Figure 4 is a front view of a modified form of the invention.

Figure 5 is a rear view thereof.

Figure 6 is a side view, and

Figure 7 is a top plan view.

55 Referring now to the drawings wherein like reference characters designate corre-

sponding parts throughout the several views, 5 designates the head of an annular member in the form of a button being provided with diametrically disposed spurs 6, 7 which 60 are adapted to dig into and engage the material of the garment and thus prevent any turning thereof. The said member 5 is preferably formed integral with the screw 8 which may pass through the material of 65 the garment adjacent to the button hole and receive the threaded back 9, the same being somewhat concave in form and substantially the same diameter as the front 70 or head 5 above referred to.

A hollow ring 10 formed with the said head 5 and substantially the same diameter is disposed at right angles thereto so that when the watch chain support is placed through the material of the garment adjacent to a button hole the chain may extend through the open ring since the same lies at right angles to the button hole. The ring 10 is open at the top as shown at 11 being bridged by the curved catch 12 provided with a small finger engaging knob 13 thereon, one end of the catch 12 bearing against a resilient spring 14 secured to a pin or stop 15 so that by forcing the catch 12 against the resistance of the spring the 85 hollow ring 10 may be opened to permit of the passage of the chain therein and the return of the catch 12 maintains said chain in position.

In the form of the invention shown by 90 Figures 4 to 7 inclusive, I have provided a similar holding device in the form of a rectangular plate 16 on which a monogram 17 may be engraved or otherwise formed, the said plate being preferably provided 95 with top and bottom extensions 18, 19, the latter being formed with a hook 20 and a raised bevelled extension 21 as clearly shown by Figure 6 of the drawing. Pivoted as at 21 to the rear of the top portion 18 there is provided a rear wall 22 preferably formed integral with the vertically extending pin 23, the said rear wall 22 being spaced from the front plate 16 so as to permit of the passing of a watch chain or eye glass bridge for 100 suspension thereon. In this form of the invention it will be seen that the front plate 16 may be moved outwardly of the rear wall 22 and the pin 23 so as to permit the chain or eyeglass bridge to be suspended on the 110 bottom extension 19 thereof, it being observed, that the lower end 24 of the rear

wall 22 is also bevelled to correspond with the bevelled extension 21 so that when the same is closed the chain will be retained in its proper position.

In the accompanying drawings, I have illustrated my invention embodied in one form by way of example, and which construction has been found to answer to a satisfactory degree the results to be obtained.

10 It would be manifest, however, that other forms of embodiment may be adopted, and that the construction may be variously changed and modified by the skilled mechanician without departing from the limits of 15 the invention. Further it will be understood that the invention is not limited to any particular form of construction in the parts, except in so far as such limitations are specified in the subject matter being claimed.

20 Having thus described my invention, what

I claim as new, and desire to secure by United States Letters Patent is:—

A chain supporting device of the class described comprising an annular head having diametrically opposed spurs extending rearwardly thereof, an open hollow ring formed integrally with the head, extending outwardly and at right angles thereto, a spring catch for said ring, a threaded pin formed with the rear of said head and a threaded 25 back cooperating with said pin and of substantially the same diameter of the head for securing the spurs to a garment.

In testimony whereof I affix my signature in presence of two witnesses.

WALTER W. LOFLIN.

Witnesses:

THOS. C. DUFFY,
J. EUGENE WILSON.
